FOREIGN PATENT DOCUMENTS

GB 2479216 A 10/2011

Primary Examiner — Marcus Jackson

(74) *Attorney, Agent, or Firm* — Lando & Anastasi, LLP

CLAIM

The ornamental design for a lamp assembly, as shown and described.

DESCRIPTION

FIG. 1 is a perspective view of one embodiment of a lamp assembly, with the center portion broken away to indicate indeterminate length;

FIG. 2 is a top view of one embodiment of the lamp assembly;

FIG. 3 is a bottom view of one embodiment of the lamp assembly;

FIG. 4 is a rear side view of one embodiment of the lamp assembly

FIG. 5 is a front side view of one embodiment of the lamp assembly

FIG. 6 is one end view of one embodiment of the lamp assembly; and,

FIG. 7 is another end view of one embodiment of the lamp assembly.

The broken lines shown in the drawing are for illustrative purposes only and form no part of the claimed design.

1 Claim, 3 Drawing Sheets
